US00D640582S

(12) United States Design Patent
Behling

(10) Patent No.: US D640,582 S
(45) Date of Patent: * Jun. 28, 2011

(54) WEIGHT

(75) Inventor: Christoph Behling, London (GB)

(73) Assignee: LVMH Swiss Manufactures S.A., La Chaux-De-Fonds (CH)

() Term: 14 Years

(21) Appl. No.: 29/362,561

(22) Filed: May 27, 2010

(30) Foreign Application Priority Data

Dec. 1, 2009 (WO) DM/072 685

(51) LOC (9) Cl. 10-04

(52) U.S. Cl. D10/128; D10/129

(58) Field of Classification Search D10/122-132;
368/125-133, 150, 160, 161, 168, 169, 325,
368/318

See application file for complete search history.
